OTTO NONNENBRUCH, OF PHILADELPHIA, PENNSYLVANIA, ASSIGNOR TO I. P. MORRIS &
DE LA VERGNE, INCORPORATED, A CORPORATION OF DELAWARE

CYLINDER CONSTRUCTION

Application filed December 19, 1930. Serial No. 503,378.

This invention relates to an improved cylinder construction for use with a reciprocating piston provided with piston rings, various applications being found for example in 5 internal combustion engines of either the gasoline or Diesel type or in pumps, compressors, etc. although the invention is particularly adapted for internal combustion engines where relatively high temperatures are encountered.

A difficulty encountered with an engine cylinder of uniform bore throughout is that the portion of the cylinder wall over which the piston rings travel is worn to a greater 15 diameter than the remaining upper portion of the cylinder which is subject only to wear by the piston itself. The result is that an annular shoulder is formed on the cylinder wall at the upper limit of travel of the top- 20 most piston ring. Any attempt to remove the piston through the top of the cylinder in order to effect any necessary repairs or inspection is obstructed or rendered difficult by the piston rings engaging the annular 25 shoulder.

To overcome the above difficulty it has been usual to counterbore the upper portion of the cylinder starting at a point very slightly below the upper limit of travel of the top 30 piston ring. This counterbore is sufficiently deep so that normally any wearing of the lower portion of the cylinder by the piston rings will not create a shoulder thus permitting relatively easy removal of the piston 35 from the cylinder. However the disadvantage of this construction is that the counterbore exposes the top piston ring to the heat of combustion thereby causing carbonization of the lubricating oil in the ring groove.

It is an object of my invention to provide an improved arrangement whereby a uniformly bored cylinder and its piston may be provided with only the usual small amount 40 of clearance throughout thereby reducing access of gases to the top ring and thus maintaining much lower temperature of the top 45 ring but yet avoiding the creation of a shoulder of such a character as will obstruct or hinder removal of the piston. It is thus seen 50 that my improved arrangement contemplates obtaining the advantages both of a uniform cylinder and the counterbore type of cylinder without incurring the disadvantages of either. A further object of the invention is to provide an extremely simple and yet effective arrangement whereby either a new or used cylinder may be arranged so as to accomplish the desired results.

A more specific object is to provide an annular groove in the cylinder wall adjacent the uppermost limit of travel of the top piston ring and to have the upper surface of this annular groove or recess suitably shaped so that after the lower portion of the cylinder becomes worn said surface will then 65 take on its function of acting as a cam or wedge to force the piston ring or rings radially inwardly if the piston is removed upwardly from the cylinder.

While the shape of this groove and its cam 70 surface may be varied it is shown herein preferably in the form of a straight inclined surface having a ratio of inclination of preferably three to one. This groove and the piston ring are so related in their dimensions 75 that if a plain piston ring is used it will bridge across the groove when passing there- over during assembly thereby preventing the ring from expanding into the groove, while if the so-called double seal piston rings are 80 used two cam surfaces are preferably pro- vided in the form of a substantially V-shape annular groove to permit insertion of the pis- ton into the cylinder without the possibility 85 of any of the small parts of the split ring being caught by any shoulder of the groove. The dimensions of a double seal ring are such 90 that it is preferable not to make the groove small enough to permit each part of the ring 95 to bridge the groove with the result that each part of the ring expands into the groove when passing the same but is gradually contracted by the lower inclined surface of the groove as the insertion of the piston con- tinues. It will be understood that if desired 100 a relatively narrow groove could be provided so as to permit each part of the ring to pass over the groove during assembly without the necessity for the second wedge or cam sur- face. However, with any of the construc-

tions, during operation the upper or advancing edge of the top ring stops above the lower edge of the groove and preferably more nearly to the point of greatest depth thereof thereby avoiding the possibility of any shoulder being created. It is thus seen that as that portion of the cylinder starting at and extending below the groove is worn by the piston rings no abrupt shoulder is formed and the piston is readily removable due to the wedge action of the upper inclined surface of what did constitute the groove.

Other objects and advantages will be apparent to those skilled in the art from the following description of the accompanying drawing in which:

Fig. 1 represents a piston and cylinder or cylinder liner provided with my improved arrangement for a double seal piston ring.

Fig. 2 is a modified form of groove adapted for a simple form of seal ring, and

Fig. 3 shows a piston being removed from a worn cylinder with the piston ring engaging the inclined surface for effecting the compressing action of the piston rings.

In the illustrated embodiment of my invention I have shown a cylinder 1 in which a piston 2 is reciprocated by any usual mechanism such for example as a rod 3 connected to a crankshaft. The cylinder as shown may be either a liner insertable within a cylinder block or it may be the cylinder casting itself. In either case an annular groove 4 preferably of substantially V shape is formed in the cylinder wall at the point where the upper or advancing edge 5 of the top piston ring 6 stops in its uppermost limit of travel. The piston ring shown in Fig. 1 is of the so-called double seal type which comprises two duplicate parts 7 and 8 matched in any suitable manner so that they retain their same relative relation at all times. Inasmuch as any of these various types of piston rings may be used it will suffice to point out that each part of the ring is usually of such a width that it would expand into the recess 4 if such a recess was made with a desirable dimension. When any part of the piston ring expands into the groove during assembly it is seen that the lower inclined surface 9 will contract the ring during downward movement of the piston and hence will permit the piston to be readily inserted in the cylinder.

In normal operation of the piston the upper part 7 of the double seal ring never completely passes the lower corner 10 of the groove thus insuring that the piston ring will at all times be supported by the wall of the cylinder and wear the cylinder wall right up to the groove. Due to the radial pressure of the rings and combustion pressure thereon the cylinder gradually wears out to a diameter such as is generally indicated by the dotted line 11 and as is shown in Fig. 3. The diameter of the greatest depth of the groove

is preferably greater than that to which the cylinder is allowed to wear so that at no time will an obstructive shoulder be formed in the cylinder wall. Hence upon removal of the piston the top edge 5 of the ring will engage the inclined surface 4' and be pressed inwardly as the piston is moved upwardly. The successive rings on the piston will likewise be pressed inwardly as they pass by the groove.

It is thus seen that by such an improved arrangement a cylinder of uniform diameter throughout may be employed thus resulting in having only the normal amount of small clearance between the piston and cylinder at the portion thereof above the groove 4. This will prevent undue exposure of the piston 7 to the heated gases of combustion thus reducing to a minimum the possibility of carbonization of lubricant in the ring groove and at the same time there is eliminated any possibility of an obstructing shoulder being formed in the cylinder wall due to wear thereof by the piston rings.

The modification shown in Fig. 2 is best adapted for a single piece piston ring, it being noted that the groove 4" has only one inclined surface namely its upper surface. The width of this annular groove is such that a single ring can entirely bridge the same thus avoiding the necessity for a lower inclined surface such as 9. The operation of this form is the same as in the other form and the advantages are also the same.

While I have specifically shown two forms which the invention may assume it will of course be understood that modifications thereof may be employed without departing from the spirit of the invention as set forth in the appended claims.

I claim:

1. In combination, a cylinder, a reciprocating piston therein, and a radially expansible sealing ring carried by said piston, the wall of said cylinder having a cam-forming groove therein adjacent the point at which the advancing edge of said piston ring stops in one limit of its travel, said cylinder on each side of said groove being of smaller diameter than the groove.

2. In combination, a cylinder having a reciprocating piston therein, and a piston ring carried by said piston, said cylinder having in its wall adjacent the limit of travel of said piston ring a groove provided with an inclined surface, whereby upon wear of the cylinder within the range of travel of the piston ring said inclined surface may act to compress the ring during removal of the piston from said cylinder.

3. In combination, a cylinder of a substantially uniform diameter throughout its working surface, a reciprocating piston therein, a radially expansible piston ring; and means normally provided as a portion of said cylinder

der whereby after wear of the cylinder within the range of travel of the piston ring said ring may be relatively easily compressed during removal of the piston from the cylinder.

- 5 4. In combination, a cylinder of a substantially uniform diameter throughout its working surface, a reciprocating piston therein, a radially expandable piston ring, and means whereby after wear of the cylinder within the 10 range of travel of the piston ring said ring may be relatively easily compressed during removal of the piston from the cylinder, said means including a groove formed in the cylinder wall adjacent the limit of travel of the 15 advancing edge of the piston ring.

5. In combination, a cylinder of a substantially uniform diameter throughout its working surface, a reciprocating piston therein, a radially expandable piston ring, and means 20 whereby after wear of the cylinder within the range of travel of the piston ring said ring may be relatively easily compressed during removal of the piston from the cylinder, said means including an annular groove 25 formed in the cylinder wall adjacent the limit of movement of the advancing edge of the piston ring and the groove having an inclined surface in advance of said limit of travel.

6. In combination, a cylinder of a substantially uniform diameter throughout its working surface, a reciprocating piston therein, a radially expandable piston ring, and means whereby after wear of the cylinder within the 30 range of travel of the piston ring said ring may be relatively easily compressed during removal of the piston from the cylinder, said means including a groove formed in the cylinder wall adjacent the advancing edge of the piston ring, the point of greatest depth of 35 40 said groove being intermediate the opposite edges thereof.

7. In combination, a cylinder of a substantially uniform diameter throughout its working surface, a reciprocating piston therein, a radially expandable piston ring, and means 45 including a cylinder wall cam-forming groove whereby after wear of the cylinder within the range of travel of the piston ring said ring may be relatively easily compressed 50 during removal of the piston from the cylinder, said means also having provision whereby the piston ring may substantially readily pass said groove in either direction thereof.

8. In combination, a cylinder of a substantially uniform diameter throughout its working surface, a reciprocating piston therein, a radially expandable piston ring, and means whereby after wear of the cylinder within the range of travel of the piston ring 55 60 said ring may be relatively easily compressed during removal of the piston from the cylinder, said means including a substantially V-shape groove formed in the cylinder wall adjacent the limit of travel of the advancing 65 edge of said piston ring.

9. In combination, a cylinder of a substantially uniform diameter throughout its working surface, a reciprocating piston therein, a radially expandable piston ring, and means whereby after wear of the cylinder within the 70 range of travel of the piston ring said ring may be relatively easily compressed during removal of the piston from the cylinder, said means including a groove formed in the cylinder wall adjacent the limit of travel of the 75 piston ring and said groove having a width less than that of the piston ring whereby said ring is adapted to bridge said groove when the piston is inserted within the cylinder.
